CLAIM

The ornamental design for a low profile flow track storage module, as shown and described.

DESCRIPTION

FIG. 1 is a perspective view of the flow track storage module as seen from the top, end and right side;

FIG. 2 is a top plan view of the flow track storage module; FIG. 3 is a right side elevational view of the flow track storage module;

FIG. 4 is a bottom plan view of the flow track storage module;

FIG. 5 is a left side elevational view of the flow track storage module; and,

FIG. 6 is a front elevational view of the flow track module, the back elevational view being a mirror image.
